UNITED STATES PATENT OFFICE.

FRANK SLATER, OF GUTHRIE CENTRE, IOWA.

DENTAL BRACKET.

SPECIFICATION forming part of Letters Patent No. 276,637, dated May 1, 1883.

Application filed September 12, 1882. (No model.)

To all whom it may concern:

Be it known that I, FRANK SLATER, of Guthrie Centre, in the county of Guthrie and State of Iowa, have invented an Improved 5 Dental Bracket, of which the following is a specification.

My invention consists in constructing a neat, strong, and durable bracket, as herein-after fully set forth, in such a manner that it 10 can be readily attached to a wall, and raised and lowered and revolved, as required in use, and folded flat against the wall and out of the way when not in use.

Figure 1 of my accompanying drawings is 15 a side view of my bracket applied to a wall. Fig. 2 is a perspective view. Together these figures clearly illustrate the construction, application, and operation of my complete invention.

20 a is a revolving angular bar secured to the wall in a vertical position by means of fixed bearings b b.

No. 1 represents a skeleton frame and arm that has mortises in the rear ends of its upper 25 and lower portions, c and c', through which the bar a extends.

d is a vertical post or brace in the rear part of the skeleton arm.

d' is a mortise in the post d.

30 f is an elbow-shaped lever that extends through the mortise d' in the post d.

f' is a mortise in the end of the lever f, that admits the lever to be slipped over the bar a with the skeleton arm c.

35 g is an elbow-shaped lever and eccentric pivoted in the front and free end of the skeleton arm No. 1, and flexibly connected with the free end of the lever f by means of a rod, h.

i is a pin projecting downward from the top 40 portion of the skeleton arm No. 1, to restrict the upward movement of the lever f.

No. 2 is a second skeleton arm, pivoted to

the front end of the arm No. 1 by means of a pin and socket, or in any suitable way.

No. 3 represents a revolving tray or case 45 adapted to retain dental instruments detachably connected with the front and free end of the arm No. 2 by means of a journal and journal-bearing.

The revolving bar a and the skeleton arms 50 Nos. 1 and 2 and the case No. 3 and the locking device may be made of wood or metal.

To retain the complete bracket at any elevation desired on the revolving bar a, I simply operate the lever g to thereby adjust and 55 lock the lever f in an inclined position, so as to cause it to bind upon the bar and clamp the complete bracket fast to the bar. To unlock I make a reverse motion with the lever g and its eccentric, as required to bring the lever f 60 into a horizontal level and right-angled or square position relative to the bar a and complete bracket; and when the lever f is in this position the complete bracket can be readily 65 raised and lowered by sliding it up and down on the bar a, to be locked and retained at any point of elevation desired by the operator.

I claim as my invention—

1. In an adjustable bracket, the locking device f g h, in combination with a skeleton arm 70 having a pin or stop, i, and a vertical bar, a, substantially as shown and described, to operate in the manner set forth, for the purposes specified.

2. The improved dental or wall bracket 75 composed of the revolving bar a, skeleton arm or frame No. 1, locking device f g h i, pivoted arm No. 2, and revolving case or tray No. 3, substantially as shown and described, for the purposes specified.

FRANK SLATER.
